CLAIM

The ornamental design for a toilet roll storage caddy as shown and described.

DESCRIPTION

FIG. 1 is an isometric view of a toilet roll storage caddy; FIG. 2 is a front view of the toilet roll storage caddy; FIG. 3 is a rear view of the toilet roll storage caddy; FIG. 4 is a side view of the toilet roll storage caddy; FIG. 5 is a side view of the toilet roll storage caddy that is opposite the side view illustrated in FIG. 4; FIG. 6 is a top view of the toilet roll storage caddy; and, FIG. 7 is a bottom view of the toilet roll storage caddy. The broken lines in the drawings show portions of the toilet roll storage caddy and form no part of the claimed design.
